UNITED STATES PATENT OFFICE.

JOSEPH DAIN, OF OTTUMWA, IOWA.

HAY-PRESS.

No. 807,911.

Specification of Letters Patent.

Patented Dec. 19, 1905.

Application filed November 1, 1902. Serial No. 129,680.

To all whom it may concern:

Be it known that I, JOSEPH DAIN, a citizen of the United States, and a resident of Ottumwa, in the county of Wapello and State of Iowa, have invented certain new and useful Improvements in Hay-Presses, of which the following is a specification, reference being had to the accompanying drawings.

This invention relates to baling-machines, and is primarily designed for use in compressing hay into bales, and is of the type employing a pull-bar for operating the compressing head or follower as distinguished from that type in which the head or follower is moved by a push imparted through the connecting-rod from the usual horse-power. In machines of this type it has heretofore been deemed necessary to employ a more or less complicated system of levers, through which the power was transmitted, in order to suitably move the head or follower, such mechanism being deemed necessary owing to the inability to make a proper direct connection of the pull-bar with the head or follower.

The object of my invention is to provide a construction whereby a direct connection of the pull-bar to the head or follower can be made which will be sufficiently strong to insure such head or follower compressing the material in the baling-case to the required extent and at the same time to so locate the pull-bar that it may extend in a direct line toward the horse-power and yet not interfere with the free compression of the material in the baling-case. To this end I provide the bottom of the baling-case with a central longitudinal slot through which the connection between the head or follower and the pull-bar can move. Inasmuch as a ridge or rib of the material being compressed would be apt to be formed upon the bale by reason of being forced down through such slot in the bottom of the baling-case during the compression of such material, I guard against such formation by providing the upper face of the connection between the pull-bar and the head or follower with a raised central portion, which enters such slot and lies substantially flush with the face of the bottom of the baling-case.

That which I regard as new will be set forth in the claims.

In the drawings, Figure 1 is a longitudinal vertical section through the baling-case and a portion of the tying-chamber. Fig. 2 is a

section at line 2 2 of Fig. 1. Fig. 3 is an end view, and Fig. 4 is an enlarged cross-section at line 4 4 of Fig. 1.

Referring to the drawings, 5 indicates a baling-case, to the upper side of which near one end is a hopper 6, through which the hay or other material to be compressed can be fed into the interior of the case 5. The baling-case shown is of ordinary construction, with the exception that it has formed in its bottom a central longitudinal slot 7, which extends to a greater or less degree under that portion of the case in which the hay is compressed, which for convenience will be termed the "baling-chamber."

8 8 indicate channel-irons suitably secured below the bottom of the baling-case 5 at each side of the central longitudinal slot 7.

9 9 10 indicate a slide which acts as a connection between the pull-bar of the machine and the head or follower, the part 10 being interposed between and suitably secured to the parts 9 and such central part 10 extending above the upper faces of the parts 9, so as to enter and close the longitudinal slot 7, as best shown in Fig. 4.

11 indicates the compressing-head or follower, located in the baling-case 5 and having a rearwardly-extending central web 12. This web 12 in the construction shown is formed integrally with the part 10, although of course it might be made separate therefrom and suitably secured thereto.

13 13 indicate a pair of rollers, each suitably journaled at one side of the web 12 and adapted to roll upon the floor of the baling-case. 14 14 indicate another and smaller pair of rollers carried near the forward ends of the pieces 9 9 of the slide and traveling within the channel-irons 8. With the device in use and the head or follower 11 pressing with great force against the material to be compressed within the baling-case it will be evident that the force exerted will tend to cause the forward ends of the pieces 9 to rise, and by the provision of these rollers 14 14 at such ends such rollers will bear against the upper turned portions of the channel-irons 8, and thereby greatly lessen friction between the parts.

15 indicates the pull-bar, which may be of the ordinary form for such pull-bars or any other equivalent construction and which is connected to the slide 9 9 10 by any suitable

means, the means shown being a hook 16 on the rear end of the pull-bar 15 and an eye 17, pivoted to the forward portion of the said slide.

18 indicates the tying-chamber, into which 5 the bale is forced from the baling-case 5 and which may be of ordinary construction.

It will be understood that the pull-bar 15 is to be connected in the usual manner to a horse-power and the head or follower 11 drawn forward, compressing the hay or other material 10 fed into the case 5 through the hopper 6 and that at regular intervals and in the usual manner the ordinary tripping mechanism of the horse-power will release the pull on the pull- 15 bar and that thereupon such pull-bar and attached parts will through the action of the compressed material in the case 5 be forced back so that the head or follower will be in position to receive in front of it another charge 20 of material, which in turn will be forced forward in the baling-case. The rebound of the pull-bar and the head in all machines of this class is very sudden, and when the connection between the pull-bar and the head or follower 25 is by means of a system of levers or other similar connections it follows as a matter of course that the rebound is very much more severe than when a direct connection is provided, as in my invention, for such system of intermediate levers or other connections in order to 30 be effective must be and is of very considerable weight. By my invention I provide, as I have found by actual use, a very effective baling device of much less weight than the 35 machines in general use and one in which the jar and shock incident to the rebound referred to is greatly diminished.

By arranging the pull-bar below the longitudinal center of the bottom of the baling- 40 case and connecting it, as shown, to the head I am enabled to get a very direct and effective pull without any liability of twisting or otherwise distorting the parts, and by the provision 45 of the raised central portion 10 of the said slide I am enabled to so close the slot in the bottom of the baling-case as to leave no objectionable ridge or rib on the finished bale, as might be the case if the hay were free to be forced down through such slot.

50 That which I claim as my invention, and desire to secure by Letters Patent, is—

1. In a baling-press, the combination with a baling-case provided with a longitudinal slot in its bottom, which extends under the baling- 55 chamber of a head or follower movable in said case, a pull-bar, and a connection between said pull-bar and head or follower, said connection extending through said slot, substantially as described.

60 2. In a baling-press, the combination of a baling-case provided with a longitudinal slot in its bottom which extends under the baling-chamber, a follower movable in said case, and connecting 65 means connecting said pull-bar with

said follower, said connecting means projecting through said slot and having means extending therein in advance of said follower. 65

3. In a baling-press, the combination with a baling-case provided with a longitudinal slot which extends under the baling-chamber, of a 70 head or follower movable in said case, a web extending rearwardly from said head or follower, a slide carried by said web and extending through said slot, said slide being extended forward of said head or follower, and a pull-bar adapted to be attached to said slide, substantially as described. 75

4. In a baling-press, the combination of a baling-case provided with a longitudinal slot, 80 a head or follower movable in said slot, a slide connected with said head or follower and projecting through said slot, a pull-bar connected with said slide and extending forwardly of the face of the plunger, and antifriction devices carried by said slide. 85

5. In a baling-press, the combination with a baling-case provided with a longitudinal slot, of a head or follower movable in said case, a slide located outside of the baling-case and having one end turned up to pass through said 90 slot and engage the rear side of the head or follower, a roller at the forward end of said slide adapted to bear against the outside of the baling-case, another roller in rear of the head or follower adapted to bear against the 95 inside of the baling-case, and a pull-bar connected with said slide, substantially as described.

6. In a baling-press, the combination of a 100 case having a longitudinal slot in its bottom which extends under the baling-chamber, a follower movable in said case, a connecting device lying under said case and having a portion projecting through said slot and connected with said follower adjacent to the operative 105 face thereof, and a pull-bar connected with the forward end of said connecting device.

7. In a baling-press, the combination with a case having a longitudinal slot in its bottom, which extends under the baling-chamber of a 110 head or follower movable within said case, and a slide projecting through said slot and engaging said head adjacent to the operative face thereof, said slide extending forward of the head and having a central portion lying 115 in said slot, substantially as described.

8. A baling-press comprising a baling-case provided with a longitudinal slot in its bottom which extends under the baling-chamber, a 120 follower movable in said case, and connecting means extending through said slot and connected to the follower adjacent to the operative face thereof.

9. In a baling-press, the combination with a baling-case provided with a longitudinal slot 125 in its bottom, which extends under the baling-chamber of a head or follower movable in said case, a web extended rearwardly from said

head or follower, a pull-bar located below said slotted bottom of the case, and means extending through said slot and connecting said pull-bar with said web, substantially as described.

10. In a baling-press, the combination with a baling-case provided with a longitudinal slot in its bottom, which extends under the baling-chamber of a head or follower movable in said case, antifriction - roller - supporting means connected with said head or follower so as to move therewith, and means extending through said slot for operating said head or follower, substantially as described.

15 11. In a baling-press, the combination with a baling-case provided with a longitudinal slot in its bottom, which extends under the baling-chamber of a head or follower movable in said case, antifriction-rollers above and below the bottom of the baling-case, means connecting both of said antifriction-rollers with said head or follower, and means extending through said slot for operating said head or follower, substantially as described.

25 12. In a baling-press, the combination of a baling-case provided with a longitudinal slot in its bottom which extends under the baling-chamber, a follower movable in said case, a connecting-bar connected to the follower and

30 extending through the slot in the baling-case, an antifriction-roller connected with said bar in advance of said follower, and another anti-

friction-roller connected with said bar at the rear of said follower.

13. In a baling-press, the combination of a 35 baling-case provided with a longitudinal slot in its bottom which extends under the baling-chamber, a follower movable in said case, a pull-bar, connecting means projecting at the rear through said slot and connected with said 40 follower, and at its forward end connected with said pull-bar in advance of the follower.

14. A follower for baling-presses, having a rearwardly-extending web adapted to be connected with pulling mechanism, and one or 45 more supporting-rollers connected with said web back of the operating-face of the follower.

15. A follower for baling-presses, having a rearwardly-extending web, a member connected with said web and extending forward of the operating-face of the follower, and one or more rollers carried by said member.

16. A follower for baling-presses, having a rearwardly-extending web, a member connected with said web and extending forward of the operating-face of the follower, one or more rollers carried by said member, and one or more rollers carried by said web back of the operating-face of the follower.
